Inventor:

Hugh H. Hendrickson,
By Cromwell Green & Warden atty.

UNITED STATES PATENT OFFICE

HUGH H. HENDRICKSON, OF ELKHART, INDIANA, ASSIGNOR TO THE ADLAKE COMPANY, OF CHICAGO, ILLINOIS, A CORPORATION OF ILLINOIS

CURTAIN ROLLER

Application filed November 2, 1931. Serial No. 572,516.

This invention has to do with curtain rollers, and is particularly concerned with rollers of the type commonly used for automobile window curtains.

5 One of the objects of the invention is to provide, in a curtain roller assembly of the type described, improved means for facilitating the removal of the roller.

Another object is to provide an improved 10 form of supporting bracket for the roller.

Another object is to provide an improved form of bung in the end of the roller.

Still another object is to provide an improved form of trunnion in the bung.

15 While the foregoing statements are indicative in a general way of the nature of the invention, other objects and advantages will be apparent to those skilled in the art upon a full understanding of the construction, arrangement and operation of the novel bracket, bung and trunnion parts.

In order that the invention may be readily understood, one embodiment of the same 20 is presented herein, but it will of course be appreciated that the invention may be incorporated in other structurally modified forms coming equally within the scope of the appended claims.

In the accompanying drawing:

25 Fig. 1 is a face view of an automobile window curtain assembly which embodies the features of the invention;

Fig. 2 is a plan view of the assembly;

30 Fig. 3 is a fragmentary horizontal section, taken on the line 3—3 of Fig. 1;

Fig. 4 is a vertical section, taken on the line 4—4 of Fig. 3;

Fig. 5 is a side view of the bung before 35 insertion in the end of the roller; and

Fig. 6 is a different side view of the bung before insertion.

The curtain assembly which is shown in the drawing includes a spring-wound roller 10; a curtain 11 on the roller; a batten 12 at the bottom of the curtain; cords 13 at the sides of the window in freely sliding engagement with eyelets in the ends of the batten; a trunnion-gripping bracket 14 at one end of the roller; and a trunnion-journaling bracket 15 at the other end of the roller.

The bracket 15 is made of sheet metal and is characterized by a hollow head portion 16 which is adapted to receive a trunnion 17. The trunnion 17 projects from the adjacent end of the roller 10 and is mounted in a 55 bung 18 which is positioned in that end of the roller.

The bracket 15 is composed of an L-shaped strip 19 and a cup-shaped cap 20. One leg of the strip 19 is apertured at 21 for the reception of attaching screws 22, while the other leg of the strip terminates in a rounded end portion 23 which is provided at its center with an opening 24. The cap 20 is positioned behind the end portion 23 of the strip 19, in cupped relation to the same, and the edges 25 of the cap are turned over the edges of the end portion 23, whereby to produce the above mentioned hollow head formation.

A disk 26 of fiber or other suitable bearing material is wedged within the cap 20 between the latter and the end portion 23 of the strip 19 and is provided, at its center, with a bearing aperture 27, of smaller size than the opening 24, for the reception of the 75 outer end of the trunnion 17. The end portion 23 is provided, about the opening 24, with an outwardly projecting annular rib 28 for rotatable engagement with a disk 29 on the end of the bung 18. The end portion 23 is 80 also provided, as a result of the annular rib formation 28, with an inwardly projecting edge 30 for fixed engagement with the bearing disk 26.

The cap 20 is provided at its center with 85 a small hole 31 in axial alignment with the bearing aperture 27 in the disk 26. The purpose of the hole 31 is to permit a small pointed tool to be inserted through the same into engagement with the end of the trunnion 17, 90 whereby to force the trunnion axially back into the end of the roller in order to dislodge the trunnion from the bracket.

The bung 18 is made for the most part of 95 sheet metal, and includes, in addition to the previously mentioned end disk 29, a U-shaped strip 32 and a small inside disk 33 of fiber or other suitable bearing material which is peripherally notched and clamped between inturned tongues 34 and shoulders 35 on the 100

ends of the U-shaped strip 32. The trunnion 17 is journaled near its inner end in a bearing aperture 36 in the center of the disk 33 and is journaled near its outer end in a bearing aperture 37 in the center of the cross web 38 of the strip 32. The trunnion also passes through an aperture 39 in the center of the end disk 29, but the last mentioned aperture is somewhat larger than the trunnion 10 and the material of the cross web 38 is sleeved through such aperture and spun out against the outer face of the disk at 40, thereby providing an extended bearing surface for the trunnion at that point.

15 The bung 18 is telescoped within the end of the roller 10, with the disk 29 on the bung in abutment with the end of the roller, and is held within the roller by the provision of indentations 41 in the sides of the same which 20 are forced into apertures 42 in the sides of the bung.

The trunnion 17 is characterized by an 25 enlargement 43 intermediate its ends, which enlargement abuts with the inner face of the cross web 38 of the U-shaped strip 32 and limits the outward movement of the trunnion. A coil spring 44 is mounted on the trunnion between the enlargement 43 and the disk 33, and serves to normally maintain the trunnion 30 in its fully projected position.

The bracket 14 at the other end of the roller may be, and preferably is, constructed like the bracket 15, but there is no occasion to have in the bracket 14 any opening corresponding to the aperture 31 in the back of the head portion of the bracket 15. The bracket 14 is preferably provided with an elongated slot in order to receive and non-rotatably engage with the ordinarily flattened 40 end of a spring-wound trunnion 45 in that end of the roller.

It will be noted in the drawing that the attaching portions of the brackets 14 and 15 are directed inwardly toward each other behind the roller. This arrangement conceals the attaching portions from sight and also permits the brackets to be attached to a short window frame member 46 which may be of even less length than the roller.

50 The above described curtain roller assembly cannot be removed in the ordinary well known way, but requires special manipulation, thereby preventing tampering and theft. In order to remove the roller, one must know of the presence and purpose of the small opening 31 in the back of the bracket 15. With this knowledge, it is a simple matter for anyone to insert a suitable tool, such as the end of a punch, a nail, or a wire, in the hole and force the outwardly spring-pressed trunnion far enough inwardly to clear the bracket.

I claim:

65 1. In a curtain roller assembly, the combination, with a roller having an axially

spring-projected trunnion at one end of the same, of an end bracket having a hollow head formation into which said trunnion projects, said head having an aperture in one wall thereof for the reception of the trunnion and 70 having another aperture in the opposite wall thereof for the reception of a dislodging tool.

2. A bracket for supporting a curtain roller trunnion, consisting of a sheet metal member which is provided with an aperture 75 of larger size than the trunnion for the reception of the latter, a sheet metal cap positioned at the back of said member in cupped relation to the same, and a centrally apertured bearing disk lodged in the cap between the latter and the member for coaction with the trunnion.

3. A bracket for supporting a curtain roller trunnion, characterized by a hollow head which is provided with an aperture in 80 one wall thereof of larger size than the trunnion, and a centrally apertured bearing disk enclosed within the head for coaction with the trunnion.

4. A bracket for supporting an axially 85 spring-pressed curtain roller trunnion, consisting of a sheet metal member which is provided with an aperture for the reception of the trunnion, and a sheet metal cap which is positioned at the back of said member in cupped relation to the same and is provided with an aperture for the reception of a tool 95 to be used in expelling the trunnion.

5. A bracket for supporting an axially 100 spring-pressed curtain roller trunnion, consisting of a sheet metal member which is provided with an aperture of larger size than the trunnion for the reception of the latter, a sheet metal cap which is positioned at the back of said member in cupped relation to the same and is provided with an aperture for the reception of a tool to be used in expelling the trunnion, and a centrally apertured bearing disk which is wedged into the cap between the latter and said member for coaction with the trunnion.

6. A curtain roller bung, comprising a centrally apertured outer end disk, a U-shaped strip having a centrally apertured cross web portion secured to said disk and having side portions for insertion in the end of a hollow roller, a centrally apertured inner end disk secured to the inner ends of the side portions of said strip, and a trunnion positioned in said apertures.

7. A curtain roller bung, comprising a centrally apertured outer end disk, a U-shaped strip having a centrally apertured cross web portion of less extent than said disk secured to the latter and having side portions for insertion in the end of a hollow roller, a centrally apertured inner end disk secured to the inner ends of the side portions of said strip, and an axially spring-pressed trunnion slidably mounted in said apertures.

8. A curtain roller bung, comprising a centrally apertured outer end disk, a U-shaped strip having a centrally apertured cross web portion secured to said disk and having side portions for insertion in the end of a hollow roller, a centrally apertured inner end disk secured to the inner ends of the side portions of said strip, a trunnion slidably mounted in said apertures, an enlargement on the trunnion between the inner end disk and the cross web for limiting outward movement of the trunnion, and a coil spring encircling the trunnion between the inner end disk and the enlargement for normally maintaining the trunnion in an outwardly projected position.

9. A curtain roller bung, comprising a U-shaped strip having a centrally apertured cross web portion and having side portions for insertion in the end of a hollow roller, a centrally apertured disk secured to the inner ends of the side portions of said strip, and a trunnion positioned in said apertures, said side portions of the U-shaped strip being provided at their inner ends with inturned tongues and shoulders between which peripherally notched portions of the disk are clamped.

10. A curtain roller bung, comprising a U-shaped strip having a centrally apertured cross web portion and having side portions, for insertion in the end of a hollow roller, a centrally apertured disk secured to the ends of the side portions of said strip, and a trunnion positioned in said apertures, said side portions of the U-shaped strip being provided at their ends with portions which interlock axially of the bung with peripheral portions of the disk.

11. A curtain roller bung, comprising a centrally apertured outer end disk, a U-shaped strip having a centrally apertured cross web portion secured to said disk and having side portions for insertion in the end of a hollow roller, a centrally apertured inner end disk secured to the inner ends of the side portions of said strip, and a trunnion positioned in said apertures, said cross web portion of the U-shaped strip being provided at its center with a small annular flange which projects through the aperture in the outer end disk and is spun outwardly about the edge of such aperture.

In testimony whereof I have hereunto subscribed my name.

HUGH H. HENDRICKSON.
